UNITED STATES PATENT OFFICE.

VANDIVER J. VAN HORN, OF CHICAGO, ILLINOIS.

COIN SAVINGS-RECEPTACLE.

1,239,143.

Specification of Letters Patent.

Patented Sept. 4, 1917.

Application filed August 28, 1916. Serial No. 117,145

To all whom it may concern:

Be it known that I, VANDIVER J. VAN HORN, a citizen of the United States, residing at Chicago, in the county of Cook and State of Illinois, have invented certain new and useful Improvements in Coin Savings-Receptacles, of which the following is a specification.

My invention relates, generally, to coin savings receptacles and has especial reference to a receptacle of this character which takes the form of an ordinary envelop, into which coins may freely be deposited, but from which they may not be extracted without, substantially, destroying the envelop.

One of the objects of my invention is to provide an inexpensive, convenient coin receptacle, preferably in the form of an ordinary envelop, provided with a coin trap encompassing a perforation through which the coin is passed into the envelop, whereby the coin may freely be inserted within the receptacle, but from which it may not be extracted without substantially destroying it.

Other, further and more specific objects of my invention will become readily apparent to persons skilled in the art, from a consideration of the following description when taken in conjunction with the drawings wherein:

Figure 1 is an elevation of a preferred form of my invention.

Fig. 2 is a similar view with parts broken away to show the inner contained coin trap.

Fig. 3 is a central vertical section taken on line 3—3 of Fig. 2.

Fig. 4 is a transverse section taken on line 4—4 of Fig. 2.

Fig. 5 is a blank, comprising, when folded, the envelop and the coin trap made in one integral piece.

Fig. 6 is an elevation of a modified form.

Fig. 7 is a similar view with parts broken away showing the inserted coin trap.

Fig. 8 is a central vertical section taken on line 8—8 of Fig. 7.

Fig. 9 is a transverse section taken on line 9—9 of Fig. 7.

50 In all the views the same reference characters are employed to indicate similar parts.

The usual coin savings receptacles are made in form of a flat, relatively thick, round or rectangular sheet metal casing which is expensive to make, inconvenient,

noisy, heavy and bulky to carry in one's pocket and which is practically as easy to be opened, by one bent upon its destruction, as if it were made of a good, tough, quality of paper or similar fibrous material.

60 A coin savings receptacle will answer the purpose for which it is intended, if it is not subject to being opened and closed without leaving evidence of the fact. It should also be of such character as to be practically 65 useless after having once been opened. A coin receptacle made of an envelop answers all of the purpose or requirements for such a retainer. Furthermore, it is convenient for placing in the side pocket of a gentleman's coat or vest, or for laying in a pigeon hole or drawer of a desk or the like. When such device is carried in a side pocket, the coins will wedge themselves down near the lower surface of the structure and will not 70 rattle or make a disagreeable noise when the person carrying it is walking or running and being in the form of an envelop it doesn't readily indicate that the receptacle 75 is of coin savings character.

80 Referring now to the drawings, 10 is the envelop or receptacle completed and ready for use. 11 is the front side wall and 12 the rear wall. The envelop may be made in any particular form, common to such structures, or in the particular form shown in Fig. 5, in which the side walls 11 and 12 are held together by the gummed flaps 13, 14 and 15. In Fig. 5, the coin chute or trap 16 is made an integral part of the side wall 12, 90 joined thereto by the neck 17 and provided with side wings 18 and 19. The lower free end of the trap is slit toward the top, as at 20, to provide a plurality of flexible fingers. The part 17 is provided with an adhesive 95 17' whereby to attach the part 17 to the side wall 12 of the envelop. The side wings 18 and 19 are provided with gummed surfaces 18' and 19', respectively.

100 In making the envelop shown in Figs. 1 to 5 inclusive, the coin trap part 16 is folded forward on the upper line of the wall 12 so that the gum surface 17' will be stuck to the wall 12. Prior to this, however, the wings 18 and 19 are folded away from the 105 observer, or rearwardly, on the dotted lines 21 and 22, respectively, and thus the gum surface 18' of the wing 18 will stick to the underside of the flap 19, and the gum surface 19' of the flap 19 will stick to the wall 110

11 under the orifice 25. The part between the vertical lines 21 and 22 will form one side of the coin chute or trap, and will overlie the perforation 25 made through the wall 11. When the wall 11 is folded over onto the wall 12, on the dotted line 26, the gummed surface 19 of the coin trap will stick to the sheet 11 and thus hold the two walls together, leaving the coin chute open, 10 as clearly shown in Fig. 4, after which the gum surfaces of the flaps 13, 14 and 15 are brought into contact with the outside surface of the wall 12 as common in construction of envelops.

15 When the coin is placed in the coin opening 25 it will enter the coin chute, between the lines 21 and 22, and pass out of the lower end thereof into the envelop. The flexible fingers 20 of the trap 16 will lie close together and prevent the possibility of permitting the contained coins to pass back through the chute and out through the orifice 25, through which they were inserted, when the envelop is inverted.

25 Figs. 6 to 9 inclusive show an ordinary envelop with a coin trap made in a separate piece and inserted therein, and secured thereto. The coin chute, or trap, is made in substantially the same manner as heretofore described, with the exception that it is made separate and apart from the envelop and is connected thereto, as at 28, above the coin slot or perforation 25. A further difference is that inside of the chute there is placed two 30 strips or blades of cardboard, 29 and 30, pointed at their lower ends, as at 31, one strip being secured near its upper end to the overlapped flaps 18 and 19, and the other to the rear wall of the chute. Normally, 35 these pointed blades are in substantial yielding contact and when a coin is inserted in the opening or perforation 25, its weight will cause the separation of the blades 30 and 31 sufficiently to permit the coins to readily pass down through the chute into the envelop, the resumption of their positions in substantial contact with each other, together with the pendent flexible fingers 20, will prevent the coin from being 40 returned through the passage through which it was inserted.

An escutcheon, or shield plate 32, made of a relatively tough material, may be placed

around the boundary of the orifice 25, to reinforce the body part of the envelop.

55

In order that the glued adhering surfaces may not be separated by steaming, as sometimes is done prior to opening envelops of the usual kind, I prefer to make the glue, which is used as an adhesive, by dissolving ordinary horn glue in milk, or the like; this renders the glue substantially insoluble by steam. There are other adhesives that have the same quality, and it is my preference to use adhesives of this general character in the manufacture of the envelops.

60

65

While I have herein shown the preferred embodiment which my invention may take and a single modification, it is manifest that it is subject to many other modifications not necessary to be shown and is limited only by the scope of the appended claims.

Having described my invention, what I claim is:

1. In a coin receptacle, the combination of 75 an envelop having a front wall with a coin slot formed therein near the upper end thereof, and a coin chute having relatively stiff front and back walls, the front wall of the chute being secured to the front wall of the envelop below the slot and the upper end portion of the back wall of the chute being secured to the front wall of the envelop above the slot.

2. In a coin receptacle, a coin trap, comprising a chute made of flexible material divided into a plurality of fingers at its free end, the fixed end communicating with a coin opening in the receptacle and a pair of flexible blades normally in contact and within said chute extending above the fingers and terminating below said coin opening.

3. In a coin receptacle, a coin trap comprising a flexible chute divided into a plurality of fingers at its free end, the fixed end communicating with a coin opening in the receptacle and a pair of flexible blades normally in contact and within said chute, pointed at their lower ends, extending from 95 a point above the fingers and terminating 100 below said coin opening.

In testimony whereof I hereunto set my hand.

VANDIVER J. VAN HORN.
